H. E. BRANDT

SPRAYER CLOSURE

Filed Aug. 28, 1924

INVENTOR
HENRY E. BRANDT
BY HIS ATTORNEY

James F. Williamson

UNITED STATES PATENT OFFICE.

HENRY E. BRANDT, OF NORTH ST. PAUL, MINNESOTA, ASSIGNOR TO DOBBINS MANUFACTURING COMPANY, OF NORTH ST. PAUL, MINNESOTA, A CORPORATION OF SOUTH DAKOTA.

SPRAYER CLOSURE.

Application filed August 28, 1924. Serial No. 734,652.

To all whom it may concern:

Be it known that I, HENRY E. BRANDT, a citizen of the United States, residing at North St. Paul, in the county of Ramsey and 5 State of Minnesota, have invented certain new and useful Improvements in a Sprayer Closure; and I do hereby declare the following to be a full, clear, and exact description of the invention, such as will enable others 10 skilled in the art to which it appertains to make and use the same.

This invention relates to a sprayer and particularly to a closure structure for said sprayer. While the invention might be applicable to different types of sprayers it is 15 particularly designed for a sprayer having a liquid receptacle and a pump cylinder extending therewith, which pump cylinder, together with the pump plunger rod is removable to permit placing the liquid in the receptacle.

It is an object of this invention to provide a very simple and efficient closure device for such a sprayer and one which will require 20 no machine finishing of parts.

It is also an object of the invention to provide a closure structure for a sprayer of the type mentioned having few parts which are ruggedly and compactly arranged for easy 25 and rapid operation.

It is a further object of the invention to provide such a sprayer closure comprising a ring secured to the receptacle about the pump cylinder opening therethrough, which ring has a 30 divided flange thereon spaced from the receptacle, which flange is formed as a pair of half threads, together with a cap adapted to extend over the said opening having a flange 35 also formed as a pair of half threads adapted to engage the half threads on said ring.

It is more specifically an object of the invention to provide such a structure as set forth in the previous paragraph, in which the receptacle has an upstanding ring formed 40 thereon about the opening therethrough, which is surmounted by a gasket engaged by a flange on the pump cylinder, said last mentioned ring, gasket and pump cylinder being surrounded by said cap, said cap acting 45 to draw said pump cylinder and gasket down on said last mentioned ring.

These and other objects and advantages of the invention will be fully set forth in the following description made in connection

with the accompanying drawings in which 55 like reference characters refer to the same parts throughout the different views, and in which,

Fig. 1 is a view in front elevation of the top portion of a sprayer showing the invention, a portion thereof being broken away and other portions shown in vertical section;

Fig. 2 is a view in front elevation of some of the parts shown in Fig. 1 in separated position;

Fig. 3 is a top plan view of a cap member used;

Fig. 4 is a top plan view of a portion of the receptacle; and

Fig. 5 is a horizontal section taken on the 70 line 5—5 of Fig. 2, as indicated by the arrows.

While the invention, as stated, is applicable to different types of sprayers, in the embodiment of the invention illustrated, the 75 same is shown as applied to a sprayer having a vertically disposed cylindrical receptacle 6 adapted to contain the liquid to be sprayed, which receptacle has a top wall 7. The wall 7 has a central circular opening 80 therein about which is punched or struck up an upstanding inwardly turned bead or ring 8. Surrounding the bead 8 and secured to the wall 7 by circumferentially spaced rivets, is a ring 9 having an inwardly disposed 85 flange spaced from the wall 7 and divided to form semi-circular portions 10 formed as helices or cam surfaces inclined in opposite directions and thus having their ends offset axially, said members thus constituting, in effect, half threads. The top of the bead or ring 8 is surmounted by a gasket 11 of annular form and a pump cylinder 12 disposed in the opening in wall 7 and substantially fitting the ring 8 has an outwardly directed 90 flange overlying gasket 11. A cap member 13 is provided formed of sheet metal having a cup-like portion surrounding the upper end of pump cylinder 12, the gasket 11 and the ring 8, which cap has a laterally directed flange divided to form semi-circular portions 14 which are helically arranged or inclined in opposite directions, thus having their adjacent ends respectively offset axially. Said flange 14 thus forms, in effect, half 95 threads which are oppositely pitched. The cap 13 has a central opening through which passes the plunger rod 15 of the pump cylinder.

100
105

der 12, which rod has at its upper end a handle 16 having a circular lower portion from which depends a pair of spaced headed pins or projections 17. The cap 13 has a pair of oppositely disposed slots 18 through which the body portions of the pins 17 can extend and said slots have central enlarged portions through which the headed portions of the member 17 may extend, said head portions, 10 however, not being movable through the end portions of the slots 18.

When assembled for operation, the upper flanged end of the pump cylinder 12 is disposed, as shown in Figs. 1 and 2, the 15 gasket 11 being pressed into the cap 13 so that it engages the shoulder therein and is held in fixed position. The handle 16 is pushed downwardly with the heads of members 17 alined with the enlargements in slots 18 and is then turned to bring said heads out of alinement with said enlargement. When flanges 14 and 10 are disengaged, the pump cylinder 12, together with the rod 15 can be lifted out of the receptacle 6 by the handle 16. The spraying liquid will then be placed in the receptacle through the central opening therein and the cylinder 12 with its rod 16 again placed in the receptacle. The gasket 11 then rests on the 30 upper edge of the ring 8. The cap 13 is now placed with the ends of the flanges 14 substantially at the ends of the flanges 10. The ends of the flanges 14 are then entered by rotating motion under the ends of the flanges 10 so that the latter overlie the former. The cap is now further rotated by turning the handle 16, the pins 17 engaging the ends of slots 18 and the flanges 14 are moved under the flanges 10. Owing to the inclined or helical formation of flanges 10 and 14 this rotatable movement draws the cap 12 downwardly and the same presses downwardly on the flanged end of the pump cylinder 12 and presses the gasket 11 firmly against the upper edge of ring 8, thus tightly sealing the opening in receptacle 6. When it is again desired to fill or empty the container 6, the handle 16 is turned in the opposite direction when the pin 16 will engage the opposite ends of the respective slots 18 and the flanges 14 will be turned from under the flanges 10 so that the pump cylinder again may be lifted out of the opening in receptacle 6. The receptacle 6 will thus be easily and quickly closed or opened by turning movement of the handle 16.

From the above description it is seen that applicant has provided a very simple, efficient and rugged closure structure for a sprayer. The ring 9, as well as the cap 13 can be quickly formed by a punching or pressing operation and no machine work is necessary therefor. The upstanding ring or bead 8 is also pressed up from the top wall 7 of the receptacle and no machine

work is necessary for this part. The ring 9 and receptacle 7 are punched and the rivets quickly inserted to secure these parts together. The entire structure, therefore, is formed without any machine finishing and 70 is made of strong sheet steel which will not easily be broken by any compact. The device has been amply demonstrated in actual practice and found to be very successful and efficient and the same is being commercially made and sold. 75

It will, of course, be understood that various changes may be made in the form, details, arrangement and proportions of the parts without departing from the scope of 80 applicant's invention, which, generally stated, consists in a device capable of carrying out the objects above set forth, such as shown and described and defined in the appended claims. 85

What is claimed is:

1. The combination with the wall of a sprayer receptacle having an opening therethrough and an outwardly projecting ring about said opening, a gasket contacting said ring, a pump cylinder having a flange overlying said gasket, a substantially annular helical means on the exterior of said wall, and a cap having helical means thereon engaging said first named helical means 95 and pump cylinder to draw the latter against said gasket.

2. A sprayer closure structure having in combination, a receptacle having an opening through the wall thereof, a ring secured 100 to the exterior of said receptacle about said opening having substantially semi-circular flanges spaced from said wall and oppositely inclined thereto, a cap having oppositely pitched helical flanges thereon adapted to 105 surround said opening and rotatably to slide under said first mentioned flanges to draw said cap toward said wall.

3. The structure set forth in claim 2, said wall having an annular inturned bead about 110 said opening, an annular gasket contacting said bead, and a pump cylinder disposed in said opening having a flange overlying said gasket, said gasket and flanged end of said cylinder being disposed in said cap. 115

4. A closure structure for a sprayer receptacle having in combination, a cap having oppositely disposed and inclined helical semi-circular flanges with offset ends and oppositely disposed and inclined semi-circular flanges secured to said receptacle also having offset ends and overhanging said first mentioned flanges. 120

5. A closure structure for a sprayer having in combination, a receptacle having an 125 opening through the wall thereof, and an inturned annular bead struck up from said wall surrounding said opening, a gasket surrounding said bead, a pump cylinder having means overlying said gasket, a ring se- 130

- cured to the outer side of said wall having oppositely disposed helical means spaced from said wall and said bead, a cap member of sheet material having oppositely disposed and pitched helical flanges thereon and adapted to engage said first mentioned helical means to draw said cap and said gasket toward said wall.
6. A sprayer closure comprising a receptacle adapted to contain the liquid to be sprayed having an opening thereto, and an annular member surrounding said opening, a pump cylinder disposed in said opening having an outer extending flange at its upper end extending over said member, a gasket between said member and flange, a cap member enclosing said flange and gasket and surrounding said member having an outwardly extending flange formed as oppositely pitched half threads with their ends axially spaced, and an overhanging flange secured to the top of said receptacle formed as oppositely pitched half threads with their ends axially spaced whereby the flange on said cap can be entered under and rotated under said last mentioned flanges to draw said cap downwardly and tighten the same in said pump cylinder flange against said gasket.
7. The structure set forth in claim 6, said cap having oppositely disposed segmental slots in its top with enlargements therein, a plunger rod reciprocable in said cylinder and through the top of said cap, and a handle at the top of said rod having downwardly extending spaced headed projections thereon, said projections extending through said slots, the headed portions thereof being movable upwardly through said enlargements but not through said slots.
8. A sprayer closure structure having in combination, a liquid receptacle having an opening therethrough, a pump cylinder having a flange thereon disposed in said opening, a gasket below said flange, and means for drawing said flange downwardly against said gasket comprising a member engaging said flange and having oppositely disposed and inclined substantially semi-circular cam flanges thereon, and a flange member on said receptacle having oppositely disposed and inclined flanges under which said first mentioned flanges are adapted to be turned.
9. A sprayer closure structure having in combination, a sheet metal receptacle having an opening in the wall thereof, and an inturned bead struck up about said opening, a gasket surmounting said bead, a pump cylinder disposed in said opening and having a flange extending over said gasket, a sheet metal cap surrounding said gasket and latter flange and contacting the latter having a laterally extending flange thereon divided and formed as oppositely pitched half threads, a ring secured to said receptacle and having a divided flange spaced from said receptacle wall and also formed as oppositely pitched half threads under which the flange on said cap is adapted to be turned to draw said cap downwardly and press said pump cylinder against said gasket.
10. The structure set forth in claim 9, said cap having a portion of slightly enlarged diameter forming a shoulder against which the lower edge of said gasket seats.
11. The structure set forth in claim 9, a piston rod extending centrally through said cap and having a handle means detachably engaging said cap and rotating the same.
12. A closure structure for a sprayer having in combination, helical flanges of circular shape substantially 180 degrees in extent overhanging the wall of said sprayer at the exterior thereof, said wall having an opening therethrough surrounded by said flanges, and a cap secured to a pump cylinder, which cylinder is adapted to enter and be disposed in said opening, said cap having outstanding helical flanges circular in form and substantially 180 degrees in extent adapted to respectively pass under and engage said first mentioned flanges to draw said cap into sealing relation with said wall.
13. A closure structure for a sprayer having in combination a receptacle having an opening therethrough, a substantially annular helical flange carried by and spaced from the top of said receptacle and surrounding said opening, and a cap having a substantially annular helical flange adapted to engage under said first mentioned helical flange and be rotated relatively thereto through substantially 180 degrees to close said opening.
14. The structure set forth in claim 13, the helical means on said receptacle being split substantially at the ends of the diameter thereof and portions thereof adjacent each of said splits being offset, the helical means on said cap also being split substantially at the ends of the diameter thereof and the portions adjacent the splits thereof being offset.
- In testimony whereof I affix my signature.
- HENRY E. BRANDT.
